DESIGN FOR A CARPET OR SIMILAR ARTICLE

Alfred Oakley, Elkins Park, Pa., assignor to Hardwick & Magee Company, Philadelphia, Pa., a corporation of Pennsylvania

Application October 26, 1940, Serial No. 96,098

Term of patent 3½ years

To all whom it may concern:

Be it known that I, Alfred Oakley, a citizen of the United States and a resident of Elkins Park, Pennsylvania, have invented a new, original, and ornamental Design for a Carpet or Similar Article, of which the following is a specification, reference being had to the accompanying drawing, forming part thereof, in which the figure is a plan view of a carpet showing my design.

I claim:

The ornamental design for a carpet or similar article, substantially as shown.

ALFRED OAKLEY.
